UNITED STATES PATENT OFFICE.

JAMES R. ROSE, OF EDGEWORTH, PENNSYLVANIA.

ELECTRIC HEATING DEVICE.

Application filed March 8, 1920. Serial No. 364,225.

To all whom it may concern:

Be it known that I, JAMES R. ROSE, a citizen of the United States, residing at Edgeworth, in the county of Allegheny and State of Pennsylvania, have invented a certain new and useful Improvement in Electric Heating Devices, of which the following is a full, clear, and exact description, reference being had to the accompanying drawings.

10 This invention relates to electric heaters and has especial reference to a heater of the reflection type wherein the heat is generated by a coil of resistance wire located approximately at the focal point of a parabolic or 15 other concave reflector whereby the radiant energy is projected in the desired direction. It is to be noted however that under ordinary conditions the heating effect of such a device upon the surrounding air is extremely small, the radiant energy not appearing as sensible heat to any appreciable extent until it falls upon some object capable of absorbing the ether waves. The objects of my invention are the provision upon such 25 a reflector of means for directly heating the air; the provision in combination with a radiant heater of means for producing a current of heated air; the provision of a new type of electric air-warming device; while 30 further objects and advantages of my invention will become apparent as the description proceeds.

In the drawings accompanying and forming a part of this application, I have illustrated certain embodiments of my invention 35 although it will be understood that these constitute only a few of the many physical forms in which my improvements can be embodied. In these drawings, Fig. 1 is a vertical sectional view through a heater of the radiant type containing my improvements; Fig. 2 represents an end view of the heating element and its adjuncts; Fig. 3 illustrates a modified form of device and Fig. 4 is an end elevation of the element shown in Fig. 3.

45 Describing by reference characters the parts shown in these drawings, 1 represents a concave reflector, generally spherical or paraboloid in form, and 2 represents the stand which supports the same. Secured in the center or vertex of this reflector is the heating element 3 shown in Fig. 1 as consisting of a spool of insulating material capable of standing high temperatures and wound 50 with resistance wire 4 and here shown as supported with its axis parallel to the axis

of the reflector. Surrounding this element and spaced therefrom sufficiently to provide an air passage is a tube 5 rigidly attached to the reflector. The spool 3 is supported in place therein in any suitable way as by the spider 6, thus permitting the passage of air. The tube 5 is preferably made of porcelain, but may be of any suitable material which will withstand the temperature to which it is subjected. Ordinarily, in practice it becomes very hot, the radiation from the exterior of the tube falling upon the reflector and being projected in the usual manner, while the air passing through the spool and tube is itself rapidly warmed. Such a circulation is almost invariably produced even though such a tube be held exactly horizontal, and is rendered all the more pronounced by an inclination of the reflector such as is usually employed.

In Figs. 3 and 4 I have shown a modified form in which the spool 3^a instead of being surrounded by a tube is itself hollowed out so as to constitute the tube, the bore 8 providing the air passage. This arrangement serves to deliver a slightly larger proportion of the total energy in the form of radiant heat and a slightly smaller proportion in the form of convection currents. In neither case, however, is there any heat lost.

It will be understood that I do not restrict myself to the employment of such an air heating means solely in condensing it with a reflector of the type herein shown, or indeed in conjunction with any reflector whatever, nor do I restrict myself in any other manner except as set forth in the claims hereto annexed.

Having thus described my invention, what I claim is:

1. The combination with a reflector-type of electric heater of means for admitting a current of air through the reflector adjacent to the heating element and in a direction whereby such entering air is warmed and ejected into the room.

2. The combination with a concave metallic reflector, of an apertured member supported in its vertex and forming an air passage through said reflector, and a resistance coil supported in juxtaposition to said passage so as both to heat the air entering the same and also to produce heat waves which are reflected from the metallic surface, said parts being so arranged that the heated air and heat waves will be ejected into the room.

3. The combination with a concave metallic reflector, of a tubular member supported in the axis thereof and opening through the vertex of the reflector through the front and 5 rear thereof, and a resistance heating element adapted to heat the air entering said tube from the rear of the reflector and passing therethrough, and also to set up heat waves which are reflected by the metallic 10 surface, said heated air and heat waves both being ejected into the room.

4. The combination with a concave metal-

lic reflector of a tubular member of heat resistant material opening through the vertex thereof and coaxial therewith, and a 15 resistance coil coaxial with said tube whereby the air traversing the tube is warmed and heat is also produced which is reflected by the metallic surface, said heated air and reflected heat being projected in the same direction into the room. 20

In testimony whereof, I hereunto affix my signature.

JAMES R. ROSE.
